Primary Examiner — Karen S Acker(74) *Attorney, Agent, or Firm* — Greenberg Traurig, LLP(57) **CLAIM**

I claim the ornamental design for a car seat protector, as shown and described.

DESCRIPTION

FIG. 1 is a front perspective view of a car seat protector; FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines and areas within them depict portions of the car seat protector that form no part of the claimed design.
